[57] CLAIM

The ornamental design for an exercise bicycle, as shown and described.

DESCRIPTION

FIG. 1 is a side perspective view of an exercise bicycle showing our new design;

FIG. 2 is a side elevational view thereof of the side opposite that shown in FIG. 1;

FIG. 3 is a front elevational view thereof;

FIG. 4 is a rear elevational view thereof; and,

FIG. 5 is a top plan view thereof.

*Fig. 1**Fig. 2**Fig. 3**Fig. 4**Fig. 5*
